(57) **CLAIM**

The ornamental design for a space light, as shown and described.

DESCRIPTION

FIG. 1 is a front perspective view of a space light, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1;

FIG. 10 is a front perspective view thereof;

FIG. 11 is a rear perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof;

FIG. 18 is an enlarged detail view of area 18 in FIG. 10;

FIG. 19 is a front perspective view thereof;

FIG. 20 is a rear perspective view thereof;

FIG. 21 is a front view thereof;

FIG. 22 is a rear view thereof;

FIG. 23 is a left side view thereof;

FIG. 24 is a right side view thereof;

FIG. 25 is a top view thereof;

FIG. 26 is a bottom view thereof; and,

FIG. 27 is an enlarged detail view of area 27 in FIG. 19.

The dash-dash broken lines in the drawings illustrate the portions of the space light, which form no part of the claimed design. The dash-dot-dash broken lines define the boundaries of the enlarged views and form no part of the claimed design.
